UNITED STATES PATENT OFFICE.

WILLIAM H. GEORGE, OF DEXTER, IOWA.

DESIGN FOR A THRESHING-MACHINE TOOTH.

SPECIFICATION forming part of Design No. 32,132, dated January 23, 1900.

Application filed December 11, 1899. Serial No. 740,030. Term of patent 14 years.

To all whom it may concern:

Be it known that I, WILLIAM H. GEORGE, a citizen of the United States, residing at Dexter, county of Dallas, State of Iowa, have invented and produced a new and original Design for a Threshing-Machine Tooth, of which the following is a specification.

Reference is had to the accompanying drawings, forming a part hereof, in which—

10 Figure 1 shows a top or plan view of the complete tooth. Fig. 2 shows a side elevation of the same. Fig. 3 shows a central longitudinal section. Fig. 4 is a transverse section through the line 4-4 of Fig. 2.
15 As shown in the drawings, the leading or essential features of my design consist in a straight cylindrical shank 10 and a flattened head 11, slightly narrower in vertical section than the shank. The front edge of the head
20 projects forwardly a slight distance beyond the shank and is straight, excepting for the rounded portion at its outer end at 12. The rear edge of the head projects a considerable

distance beyond the shank, thus forming a square shoulder at right angles to the shank, 25 and the rear edge is made slightly concave at 13. The round shank is provided at the intersection of the shank and the head with squared shoulders 14, which form at the intersection of the shank and the head a substantially rectangular figure in cross-section. The sides of this rectangular figure are curved 30 inwardly and toward the outer end of the head at 16, and the front edge of this squared portion tapers inwardly toward the shank 35 at 15.

Having thus described my invention, what I claim as new, and desire to secure by Letters Patent of the United States, is—

The design for a threshing-machine tooth 40 substantially as herein shown and described.

WILLIAM H. GEORGE.
